UNITED STATES PATENT OFFICE.

CALVIN H. MAISH, OF CARSON CITY, NEVADA.

DESIGN FOR AN EASEL.

SPECIFICATION forming part of Design No. 21,143, dated November 3, 1891.

Application filed August 31, 1891. Serial No. 404,343. Term of patent 14 years.

To all whom it may concern:

Be it known that I, CALVIN H. MAISH, a citizen of the United States, residing at Carson City, in the county of Ormsby and State of Nevada, have invented and produced a new and original Design for Easels, of which the following is a specification, reference being had to the accompanying drawings, forming a part thereof.

10 This design relates to the ornamentation of easels, and more particularly to that class which is adapted to support a music-portfolio.

The leading features of the design consist in the ornamental work which appears upon 15 the side pieces of the easel and the frame supported between the upper ends of the same, of the ornamental tops and feet of the side pieces, of the ornamentations of the cross-pieces connecting the lower portions of the 20 side pieces, of the ornamental support and stays, of the ornamental figure sustained between the cross-pieces, the ornamentation of the cover of the portfolio, and the scroll-work secured at various places.

25 In the drawings, Figure 1 is a front elevation, and Fig. 2 is a perspective view, of an easel, illustrating the design.

Referring to the drawings by letter, A A 30 designate the side pieces; B B, the cross-pieces secured between the lower ends of the side pieces; C, the portfolio secured midway between the side pieces, and D the cover for the same, adapted to form a shelf; E, the frame supported between the upper ends of 35 the side pieces; F, the support, and G G the stays adapted to sustain the several parts in their adjusted positions.

The side pieces A A are ornamented on their front faces, which are slightly curved transversely by the indentations or flutes a, extending nearly their entire length, and which 40 are crossed at intervals by the diagonal bands

a'. Their upper ends are ornamented by the conical-shaped tops b and their lower ends by the claw-feet o, the shanks of the latter being 45 twisted.

The cross-pieces B B are ornamented by the bands of floral representations b² b² and the bands b' b' of pyramidal projections. Vertically between the cross-pieces is supported 50 the lyre-shaped ornament C'. The corners formed by the joining of the cross-pieces are ornamented by the triangular-shaped pieces of scroll-work c c.

The outer edge of the face of the portfolio-cover D is formed into the shape of a frame and is ornamented by the band d of pyramidal projections, inside of which is a band e of floral representations. Inside of the band e is another band of irregular flutings. 55

H is the picture of a face ornamenting the space inside of the inner band. From the lower edge of the cover a ledge I projects, the outer face of which is slightly rounded and is ornamented by the flutings f. 60

The outer face of the frame E is ornamented in a manner similar to that of the side pieces.

K is the picture of a landscape ornamenting the interior of the frame.

L is a triangular-shaped piece of scroll-work 70 ornamenting the top of the frame.

The upper end of the support F is formed of the ornamental scroll-work m.

Having thus described my invention, what I claim, and desire to secure by Letters Patent, is—

The design for an easel, as herein described and shown.

In testimony whereof I affix my signature in presence of two witnesses.

CALVIN H. MAISH.
